FEED MECHANISM FOR PHONOGRAHS

Frank Rieber, Los Angeles, Calif., assignor to
Memovox, Inc., Beverly Hills, Calif., a corpora-
tion of Ohio

Original application April 28, 1941, Serial No.
390,690. Divided and this application August
2, 1941, Serial No. 405,176

9 Claims. (Cl. 74—424.8)

This invention relates to phonographs, and more particularly to the feed mechanism for advancing the recording or reproducing head over the record.

This application is a division of an application entitled "Phonograph apparatus," filed in the name of Frank Rieber, on April 28, 1941, Serial No. 390,690, and a continuation in part of an application filed in the name of Frank Rieber, on November 27, 1939, Serial No. 306,244.

It is common in phonographs, regardless of whether a record in the form of a disc, a cylinder, or a loop or belt is utilized, to include mechanism for positively causing the cooperating sound head to traverse the record. Such mechanisms usually include a threaded rod or "feed screw" rotated by a suitable mechanical means at a definite rate with respect to the speed of the record. The sound head is mounted on a carriage guided for movement transversely of the record, and connected to the feed screw by appropriate means such as a threaded nut. Since it is desirable to be able to move the carriage independently of the feed screw, the feed nut or other means is arranged to be disengaged from the feed screw when desired. One way in which this can be done is to have the nut embrace not more than half the circumference of the feed screw. Thus, by appropriately supporting the nut, it can be moved in a generally radial direction to or from engagement with respect to the feed screw, as desired.

It is an object of this invention to provide an improved screw feed of this character.

It is another object of the invention to provide such feed mechanism having a novel form of feed nut which may be readily and quickly engaged or disengaged with respect to the feed screw.

It is still another object of the invention to provide improved means for supporting the feed nut with respect to the feed screw so that any relative misalignment of the parts will have no deleterious effects on the drive and the nut will remain in proper operative position, and without any binding effects.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, 55

since the scope of this invention is best defined by the appended claims.

In the drawings:

Figure 1 is a top plan view partly broken away of a phonograph incorporating the invention; Fig. 2 is an enlarged detail view of a fragment of Fig. 1, showing the feed nut;

Figs. 3 and 4 are sectional views as seen on correspondingly numbered planes of Fig. 2; and 10 Fig. 5 is a pictorial view of the feed nut.

Referring to Fig. 1 of the drawings, a known type of phonograph is shown comprising a turntable 1 carrying a record disc 2 and supported for rotation about a vertical axis by a framework 3. This frame includes guide bars 25 and 26 which slidably support a carriage 9 on which is mounted the sound head 11, which may be either a recorder or a reproducer.

Mechanism of any suitable type is provided for 20 rotating the turntable 1, and means are provided for advancing carriage 9 to cause the stylus (not shown) carried by sound head 11 to traverse the record.

This means comprises the lead screw 7, rotatably supported in frame 3 and connected with the means driving the turntable, so as to be driven thereby, and feed nut 120 carried by the carriage 9 and engaging feed screw 7. Thus, rotation of lead screw 7 causes a corresponding 30 advance of carriage 9.

It is necessary at times, incident to the operation of the phonograph to alter the position of the sound head 11 relative to the record 2, as well as to return the head 11 to starting position after reaching the end of the record. This involves disengaging the feed nut 120 from the feed screw 7.

To facilitate the engagement and disengagement of nut 120 with respect to feed screw 7, 40 nut 120 comprises a pair of fragmentary nuts or bands 121 and 122 internally threaded and axially spaced, joined by a yoke 123. Bands 121 and 122 occupy oppositely disposed angular portions of a complete circumference, so as to engage the threads of lead screw 7 on diametrically opposite portions thereof. In this way a rotation 45 of yoke 123 about an axis 124, between the bands and radial to screw 7 serves either to engage or disengage the threads of bands 121 and 122 with respect to the threads of screw 7. Obviously, one band could be omitted, the remaining band being relied on to move the carriage, and being adapted to be moved to or from the screw 7 in the same manner by swinging about axis 124. 50 However, two bands are preferable since with

such an arrangement, the force exerted by screw 1 to move frame 9 has least tendency to force nut 120 out of engagement with the screw threads.

In order to permit such rotation, as well as to connect nut 120 operatively to carriage 9 so that movement imparted to nut 120 will serve to advance the carriage, a shaft 125 is fastened to yoke 123. Shaft 125 is supported for rotation about its axis 124 by a guide 126 attached to carriage 9.

Shaft 125 is also axially movable in guide 126, to permit nut 120 to accurately accommodate itself to screw 1. A compression spring 133 surrounds shaft 125 and is confined between the top of guide 126 and hub 134 of a crank arm 137 secured to the upper end of shaft 125. This is to ensure proper engagement between the threads of nut 120 and of lead screw 1.

To provide additional resilience in the structure as well as adjustment, guide 126 is secured to flat supporting springs 128 on opposite sides of the guide, as by screws 127. Springs 128 have sloping portions 129 with the same inclination as axis 124, terminating in horizontal portions 130 secured to the top of carriage 9 as by screws 131. For purposes of adjustment, slotted holes 132 may be provided in spring portions 130 for the screws 131.

Shaft 125 is moved clockwise about its axis 124 to bring bands 121 and 122 into engagement with lead screw 1. This may be conveniently accomplished for example by the aid of a tension spring 135, one end of which is secured to crank arm 137, the other end being anchored to a post 136 on carriage 9.

It is to be noted that by virtue of the resilient supporting elements 128, and the freedom of motion of the shaft 125 permitted by springs 133 and 135, nut 120 can follow accurately the threads on screw 1, even though there be some misalignment or even a slight bending of the screw 1.

When it is desired to disengage nut 120 from the screw 1, shaft 125 is turned counterclockwise through a small angle as viewed in Fig. 2. For this purpose a link 174 is slidably supported in a bracket 175 on carriage 9. One extremity of link 174 is bent up as indicated by 176 in Figs. 3 and 4, so as to engage and rotate crank 137 in response to outward (upward in Figs. 1 and 2 of the drawings) axial movement of link 174. This movement may be imparted by any suitable means, conveniently acting on the opposite end of link 174.

What I claim is:

1. In mechanism for advancing a sound head, a carriage supporting the head, a guide for the carriage, a lead screw, a threaded fragmentary nut engaging the screw, and means on the carriage pivotally supporting said nut for rotary movement into or out of engagement with said screw, said pivotal support means having an axis substantially radial to the feed screw and spaced along the screw from said nut.

2. In mechanism for advancing a sound head, a carriage supporting the head, a guide for the carriage, a lead screw, a threaded fragmentary nut engaging the screw, means forming a pivotal support for the nut, said pivotal support means having an axis substantially radial to the feed screw and spaced along the screw from said nut, and a

resilient bracket carried by the carriage, supporting said pivotal support means.

3. In mechanism for advancing a sound head, a carriage supporting the head, a guide for the carriage, a lead screw, a threaded fragmentary nut engaging the screw, means on the carriage pivotally supporting the nut, said pivotal supporting means having an axis substantially radial to the feed screw and spaced along the screw from said nut, and means for rotating said nut about said axis.

4. In mechanism for advancing a sound head, a carriage supporting the head, a guide for the carriage, a lead screw, a threaded fragmentary nut engaging the screw, a shaft on said nut, said shaft having an axis radial to the thread of the nut and spaced along the screw from said nut, a bracket on the carriage pivotally supporting the shaft, means resiliently supporting said shaft against axial movement in the bracket, and means to revolve the nut about said axis.

5. In a mechanism for advancing a phonograph head, a lead screw, a carriage supporting the head, a nut engaging the screw, said nut having a pair of interrupted axially spaced threaded bands, and means supported on the carriage for forming a pivot for the nut along an axis radial to the screw and intermediate said bands said nut being rotatable about said pivot to engage or disengage said screw.

6. In a mechanism for advancing a phonograph head, a lead screw, a carriage supporting the head, a nut for engaging the screw, said nut having a pair of interrupted axially spaced threaded bands, means supported on the carriage for forming a pivot for the nut along an axis radial to the screw and intermediate said bands, and resilient means urging said nut to rotate about said radial axis, for engagement with the screw.

7. In a mechanism for advancing a phonograph head, a lead screw, a carriage supporting the head, a nut for engaging the screw, said nut having a pair of interrupted axially spaced threaded bands, means supported on the carriage for forming a pivot for the nut along an axis radial to the screw and intermediate said bands, resilient means urging said nut to rotate about said radial axis, for engagement with the screw, and positive means for moving the nut out of engagement with the screw.

8. In a mechanism for advancing a phonograph head, a lead screw, a carriage supporting the head, a nut engaging the screw, said nut having a pair of interrupted axially spaced threaded bands, said interrupted portions of the two bands occupying diametrically opposite sides of the nut, means forming a pivot for the nut along an axis radial to the screw and intermediate said bands, and a resilient bracket carried by the carriage and supporting said pivot means.

9. A feed nut for use in advancing a phonograph carriage comprising a pair of axially spaced fragmentary threaded bands adapted to cooperate with a feed screw, said bands having a common axis as well as equal angular extents of less than 180° and being diametrically opposite each other, a yoke connecting said bands, and a shaft for supporting the nut joined to said yoke, intermediate the bands and perpendicular to their axis.

FRANK RIEBER.
